VACUUM CLEANER

Norman A. Moecker, Elmhurst, Ill., assignor to Whirlpool Corporation, a corporation of Delaware

Filed Aug. 26, 1957, Ser. No. 680,221

9 Claims. (Cl. 285—7)

This invention relates to a vacuum cleaner and particularly to a wand lock therefor.

One of the features of this invention is to provide an improved vacuum cleaner wand lock which may be easily assembled with telescoping wand tubes and which is made of easily formed, simply constructed parts.

Other features and advantages of the invention will be apparent from the illustrative embodiment of the invention shown in the accompanying drawings. Of the drawings:

Figure 1 is a fragmentary plan view showing a vacuum cleaner wand lock illustrating one embodiment of the invention;

Figure 2 is an exploded view partially in section of the telescoping wand tubes and the parts forming the vacuum cleaner wand lock;

Figure 3 is an enlarged vertical section substantially along line 3—3 of Figure 1 with the parts shown in locking position and showing the inner wand tube in a full line position and a second broken line limit position;

Figure 4 is a vertical transverse sectional view substantially along line 4—4 of Figure 3; and

Figure 5 is a view similar to Figure 4 but showing the wand lock in open position.

In the embodiment shown in the accompanying drawings the wand lock, indicated generally at 10, is assembled with an outer wand tube 11 and an inner wand tube 12 telescopically mounted within tube 11 for sliding movement relative thereto for locking the tubes together in a desired position. The outer wand tube 11 is flared outwardly at an end 11a to provide an increased clearance between the wand tubes 11 and 12 to provide space for parts of the wand lock 10.

The wand lock 10 comprises a manually rotatable lock member 15 in the form of a lock ring externally mounted on the end 11a of the outer wand tube 11 for controlling the locking of the wand tubes together and a flexible friction member 16 in the form of a ring positioned between the wand tubes 11 and 12 and deformable by the lock ring to tightly engage the inner wand tube 12, and lock the wand tubes together. Each of these rings may be formed of molded plastic material and, more particularly, the lock ring 15 is formed of nylon and the friction ring 16 is formed of polyethylene.

As shown in Figure 3, the lock ring 15 and the friction ring 16 are held on the outer wand tube 11 by means including a retaining catch member in the form of a pin 17 extending through an opening 18 in the wall of the outer wand tube 11 of a size to surround and receive the pin. The catch member 17 at one end loosely fits into a cavity 19 as defined by an internal annular groove formed in the lock ring 15, and at its other end has a base 20 loosely fitted in a cavity 21 as defined by an external annular groove formed in the friction ring 16. The base 20 is formed similarly to a base 25 for the cam follower member 22 to be described subsequently and has curved top and bottom sides to conform with the curvature of the friction ring 16 and outer wand tube 11.

2

This structure permits rotation of the lock ring 15 relative to the outer wand tube 11 and holds the lock ring 15 and friction ring 16 on the outer wand tube 11.

A second pin 22, substantially identical to the pin 17, 5 constitutes a cam follower member for either releasing or clamping the flexible friction ring 16 to the inner wand tube 12. The pin 22 extends through a second opening 23 in the wall of the outer wand tube 11 axially spaced from the opening 18 and of a size to surround and receive the pin 22.

The cam follower pin 22 at one end engages with an internal cam surface 24 formed as a groove in the lock ring 15. The groove defining cam surface 24 has a maximum depth as indicated at 24a and gradually decreasing depth at both sides of the maximum depth until the cam surface merges into the inner peripheral surface of the lock ring as indicated at 24b and 24c. The opposite end of the cam follower pin 22 has a base 25 which loosely fits in an external annular groove 26 formed in the friction ring 16. As shown in Figures 4 and 5, the base 25 is formed to have a relatively thin elongated shape with curved top and bottom surfaces so as to conform to the curvature of the outer wand tube 11 and the friction ring 16.

25 With the lock ring 15 held for rotation on the outer wand tube 11 by the catch member 17, the flexible friction ring 16 may be placed in tight engagement with the inner wand tube 12 by causing the cam follower member 22 to travel along the cam surface 24 from the area 24a in either direction toward either point 24b or 24c. This operation is illustrated by comparison of Figures 4 and 5 wherein, in Figure 5, the maximum depth area 24a of the cam surface 24 is adjacent to the cam follower member 22. In this location of the parts there is no deformation 30 of the friction ring 16 so that the inner wand tube 12 may be freely moved lengthwise within the outer wand tube 11. In Figure 4, the lock ring 15 has been manually rotated from the position of Figure 5 to have the cam surface 24 shift the follower member 22 radially inward 35 to deform the flexible friction ring 16 into tight engagement with the inner wand tube 12.

To aid in holding the friction ring 16 on the outer wand tube 11, a third external annular groove 30 is formed in the friction ring and receives an inturned flange 31 which may be an annular burr left on the inner diameter 40 of the outer wand tube 11 as formed during the process of cutting off a length of tubing to form the outer wand tube 11.

The inner wand tube 12 may take any position less than 45 fully extended relative to the outer wand tube 11, one such position being shown in full line in Figure 3, and has a limit of extension, as shown in broken line. This limit is determined by a snap ring 32 fixed in an external annular groove 33 on an end of the inner wand tube 12 which engages an end of the friction ring 16. This snap ring also serves as a spacer between the wand tubes 11 and 12 to facilitate their relative sliding movement.

As shown in Figure 1, a pair of inserts 35 and 36 are placed in the outer wand tube 11 and lock ring 15, respectively. These inserts, when in alignment, indicate 50 that the cam follower member 22 is adjacent the maximum depth 24a of the cam surface 24 whereby the inner wand tube 12 may be freely adjusted relative to the outer wand tube 11.

In the wand lock of this invention the parts may be 55 easily assembled by first placing the lock ring 15 over the end of the outer wand tube 11. The catch member pin 17 and the cam follower member 22 are then positioned in the openings 18 and 23 in the outer wand tube 11 with their ends lying in the lock ring internal groove 19 and maximum depth area 24a of the cam 24 respectively. The friction ring 16 is inserted into tube 11 thereby 60

holding catch member pin 17 and cam follower member 22 in their working positions as shown in the drawings. The inner wand tube 12 is then inserted full length into the outer wand tube to project the tube 12 and groove 33 therebeyond and the snap ring 32 is then positioned within its groove. The friction ring 16 flexes sufficiently to permit the catch member base 20 to fit in the friction ring groove 21, the cam follower member base 25 to fit in the friction ring groove 26, and the burr 31 to fit the friction ring groove 30.

The friction ring 16 has an outturned flange 40 formed at an end thereof to abut against an end of the lock ring 15 and the outer wand tube end 11a. This flange properly locates the two rings on the outer wand tube 11 and in alignment with the parts which engage said rings.

The lock ring 15 and the friction ring 16 are easily formed as molded parts having simple internal and external grooves, respectively, and large quantities may be produced economically. The rings 15 and 16 and, in addition, the retaining member pin 17 and cam follower member pin 22 are all that must be easily assembled with the wand tubes to provide a vacuum cleaner wand lock.

Having described my invention as related to the embodiment shown in the accompanying drawings, it is my intention that the invention be not limited by any of the details of description, unless otherwise specified, but rather be construed broadly within its spirit and scope as set out in the accompanying claims.

I claim:

1. A vacuum cleaner wand lock for locking a pair of telescoping wand tubes comprising: a molded lock ring loosely mounted on the outer of said wand tubes, said lock ring having an annular internal groove and an internal cam surface formed as a groove having a maximum depth and gradually decreasing depth at both sides thereof until said groove merges into the inner peripheral surface of the lock ring; a molded friction ring formed of flexible material positioned between the wand tubes, said friction ring having three spaced apart external annular grooves; means defining a pair of axially spaced openings through the wall of the outer wand tube; a catch member extending through one of said holes and engageable in the lock ring annular groove and one of the friction ring annular grooves for holding the rings on the outer wand tube; and a cam follower member extending through the other of said openings and engageable with the cam surface and in a second of said friction ring grooves to force the friction ring into tight engagement with the inner of said wand tubes when the lock ring is rotated to shift the maximum depth section of the cam surface away from the follower; the third of said friction ring grooves receiving a burr on the inner diameter of the outer wand tube to aid in holding the friction ring.

2. A vacuum cleaner wand lock as defined in claim 1 in which the catch member and cam follower member are each formed as a pin to loosely fit in the outer wand tube holes and have an enlarged base with curved top and bottom surfaces positioned in the first and second friction ring grooves.

3. A vacuum cleaner wand lock as defined in claim 1 in which a snap ring is fitted in an annular groove in the inner wand tube end positioned within the outer wand tube to limit the extension of the tubes relative to each other by engagement of the snap ring with an end of the friction ring.

4. A vacuum cleaner wand lock as defined in claim 3 in which the lock ring and outer wand tube have means for indicating when the lock ring is rotatively positioned to free the friction ring from tight engagement with the inner wand tube.

5. A vacuum cleaner wand lock for locking a pair of telescoping wand tubes comprising: a lock ring loosely mounted on the outer of said wand tubes, said lock ring having an annular internal groove and an internal cam surface formed as a groove having a maximum depth

and gradually decreasing depth at both sides thereof until said groove merges into the inner peripheral surface of the lock ring; a friction ring formed of flexible material positioned between the wand tubes, said friction ring having a pair of spaced apart external annular grooves; means defining a pair of axially spaced openings through the wall of the outer wand tube; a catch member extending through one of said openings and engageable in the lock ring annular groove and one of the friction ring annular grooves for holding the rings on the outer wand tube; a cam follower member extending through the other of said openings and engageable with the cam surface and in a second of said friction ring grooves to force the friction ring into tight engagement with the inner of said wand tubes when the lock ring is rotated to shift the maximum depth section of the cam surface away from the follower.

6. A vacuum cleaner wand lock for locking telescoping inner and outer wand tubes in a desired relative position, comprising: a lock member movably mounted on the outside of the outer wand tube, said lock member having an internal cam surface; a flexible friction member between the wand tubes having a pair of spaced external grooves; means including a retaining member in an opening in the outer wand tube wall engaging one of said grooves in the friction member and engaging the lock member for holding these members on the outer wand tube; and a cam follower in an opening in the outer wand tube wall engaging said cam surface and the other of said grooves in the friction member and movable inwardly by the cam upon movement of the lock member to press the friction member against the inner wand tube and lock the tubes together.

7. The vacuum cleaner wand lock of claim 6 wherein said lock member is circumferentially oscillatable on said outer wand tube and the pair of grooves extend arcuately in the direction of oscillation.

8. A vacuum cleaner wand lock for locking a pair of telescoping wand tubes comprising: a lock ring loosely mounted on the outer of said wand tubes, said lock ring having an annular internal groove and an internal cam surface axially spaced from the groove also formed as a groove having a maximum depth and gradually decreasing depth at both sides thereof; a friction ring of flexible material positioned between the wand tubes, said friction ring having a pair of axially spaced external annular grooves; means defining a pair of axially spaced openings through the wall of the outer wand tube; a catch member extending through one of said holes and engageable in the lock ring annular groove and one of the friction ring annular grooves for holding the rings on the outer wand tube; and a cam follower member extending through the other of said openings and engageable with the cam surface and in the other of said friction ring grooves to force the friction ring into tight engagement with the inner of said wand tubes when the lock ring is rotated to shift the maximum depth section of the cam surface away from the follower.

9. A vacuum cleaner wand lock for locking telescoping inner and outer wand tubes in a desired relative position, comprising: a lock member movably mounted on the outside of the outer wand tube, said lock member having an internal cam surface; a flexible friction member between the wand tubes; means including a retaining member in an opening in the outer wand tube wall engaging the friction and lock members for holding these members on the outer wand tube; and a cam follower in an opening in the outer wand tube wall engaging said cam surface and friction member and movable inwardly by the cam upon movement of the lock member to press the friction member against the inner wand tube and lock the tubes together, the friction member having three axially spaced external grooves, one groove receiving said retaining member for holding the locking and friction members on the outer wand tube, a second groove receiv-

ing the cam follower, and the third groove receiving an inturned flange on the end of the outer wand tube.
